UNITED STATES PATENT OFFICE.

HUGH D. FITZPATRICK, OF GLASGOW, SCOTLAND, ASSIGNOR TO ERNEST HAYWARD FAIRBANKS, OF PHILADELPHIA, PENNSYLVANIA.

DISK-RECORD CABINET.

Application filed May 28, 1921. Serial No. 473,255.

To all whom it may concern:

Be it known that I, HUGH DONALD FITZPATRICK, of 94 Hope Street, Glasgow, Scotland, a subject of the King of Great Britain, have invented certain new and useful Improvements in Disk-Record Cabinets, of which the following is a specification.

This invention relates to containers or cabinets for holding disk records, such as used for gramophones and like instruments, and its main object is to so construct the cabinet or container that its capacity can be increased or decreased at will. For instance; the cabinet may be arranged to hold, say, twenty disk records, but, if it is desired to make it to hold forty records, then its capacity can be increased accordingly. A secondary object is to so make the cabinet that it can be readily closed without the use of swinging doors, which, when opened, take up space and are otherwise objectionable.

According to this invention, the cabinet comprises a suitable frame or case which, in outward appearance, may be like the usual gramophone cabinets, and is or may be supported on four legs, and is so made as to hold, as desired, one or more record containing receptacles, or storage cells (as I call them) which latter can be readily inserted in place in the frame and removed therefrom. The cabinet is provided with a movable flexible cover adapted to be pulled down over the front of the storage cell or cells, when fitted in the frame, and to exclude dust and dirt therefrom, and to form a neat closure. The whole arrangement is such that, for normal use, a single cell may be placed in the frame, but, when it is desired to extend the capacity of the cabinet, one or more additional cells can be fitted in the frame, the length of the flexible cover being such that it can be made to cover over the front of a single cell or all of the cells, as desired.

Each storage cell is, preferably, of rectangular form, in cross section, and is provided with an inclined false bottom sloping downwardly to the front thereof, and is divided into compartments by a series of spaced paper board or other partitions, which may be either fixed or removably fitted in tongued bars for holding the partitions in spaced relationship, each compartment being adapted to receive a disk record. Each cell is self contained and is adapted

to slidably fit into the frame so as to be easily withdrawn therefrom when desired, and can, when inserted, be held in position by gravity action or by screws, pegs, catches or other devices. The invention also covers other improvements as hereinafter described and claimed.

The invention will be hereinafter described in connection with the accompanying drawings, whereon are illustrated, by way of example, constructions of cabinets and cells.

Referring to the drawings:—

Fig. 1 is a perspective elevation of a gramophone disk record containing cabinet shewn with a roll-top cover partly opened.

Fig. 2 is a transverse sectional elevation of the cabinet shewn in Fig. 1.

Fig. 3 is a similar view to Fig. 2, illustrating the provision of a roller blind in place of the roll-top.

Figs. 4 and 5 are perspective views, partly in section, of parts used in the construction of the cells in which the records are placed; and Fig. 6 is a detail view, partly in section, illustrating a manner of movably mounting in position a guard *c*.

Fig. 7 is a perspective view of one of the self-contained cells drawn to a different scale.

The cabinet shewn in Figs. 1, 2, and 3, is fitted with two removable storage cells *a* and *a'*, one above the other, and each of the cells, when located in position, has the bottom or floor *b* inclined downwardly towards the front or open side. With such an arrangement, the disk records always tend to roll forwards by gravity, from out of each cell to a position in which they are readily available for use, being held in such position by a suitable movable guard or arresting rail *c* provided in connection with each cell. The guard *c* serves also as a means for returning the records into the cell corresponding thereto, and when the guard of each is in the closed position, the cells can be enclosed within the cabinet by a flexible cover *d*.

The cell *a* or *a'*, comprises upper, lower, rear and end walls of thin wood or other appropriate material suitably secured together and fitted with a series of partitions *e* for subdividing the cells into a series of parallel compartments.

In the construction shewn in the drawings,

the adjoining edges of the rear wall and the upper and lower walls are secured to each other in any well known way, and, in this connection, are fitted with bars f which extend from end to end of the cell. Each of the upper and lower bars f is, preferably, of rectangular cross section, as shewn in Fig. 5, and is formed with a series of triangular tongues f^1 which extend from one corner edge to nearly a diagonal line extending between the two adjacent corners. Between the tongues f^1 are fitted the rear upper and lower portions of the partitions e , such portions being formed with bevelled corners adapted to engage between the tongues and bear against the bottom of the slots between the tongues. The bars serve as means for strengthening the corners between the rear wall and the upper and lower walls, and also serve for spacing the rear ends of the partitions, the front ends of the partitions being spaced by a bar g , Fig. 4, formed with a series of tongues g^1 between which the upper portions of the front ends of the partitions are disposed when the bar g is fitted into position and secured to the upper wall of the cell.

The inclined bottom or floor b of each cell, is, or may be, arranged as a false bottom thereto, and beneath such bottom or floor may be provided an outside lower wall b^1 , spacing blocks or pieces b^2 being located between the false bottom b and outside lower wall b^1 to properly support the false bottom at the desired angle on the outside wall b^1 .

The outside lower wall b^1 may be dispensed with, if desired, and the downwardly inclined bottom or floor b would, in this case, constitute the outside wall of the cell and be supported on cross bars, such as h , forming part of the cabinet. Where this arrangement is provided, the cross bars h are made as solid rectangular supports, but having an upper surface downwardly inclined to the front. The cells can be secured in position against movement relatively to the cabinet, by screws, pins or the equivalent thereof passed through the bottom into the front bar h^1 .

Where the inclined false bottom is provided with a lower outside wall, the cross bars h may be angled, as shewn at Fig. 2 with a horizontal flange part h^2 and a vertical flange part h^3 . Such angled bars constitute a back stop as well as a support for the cell. Preferably the level of the flange part h^2 would be slightly lower than the level of the bar h^1 so that when a cell, with its false bottom, is slid into position within the cabinet, it will tilt backwards and downwards and thereby tend to remain in position under the action of gravity; screws and like fastening being unnecessary.

The cross bars h are secured to supports j^1 provided on the sides j of the cabinet, such

sides being connected to each other by a top member j^2 and a rear member j^3 , while each is provided with front and back legs j^4 which serve to support the cabinet at a suitable height from the floor, while the front legs are forwardly pitched as hereinafter set forth.

The movable guards c , besides serving to hold and retain the records within the cells, as shewn in the lower part of Fig. 2, also serve to retain the disk records x , as shewn in Fig. 1 and the upper part of Fig. 2 in a position for facilitating the withdrawal of any one or more disk records for use, and prevents them rolling out on to the floor. Each guard is preferably, of triangular form in cross section, as shewn in Fig. 2, and is mounted on side arms c^1 in such a manner, as to present the side c^2 of the guard corresponding to the hypotenuse of the triangle, to the edges of the disks. Each side arm c^1 , as shewn in Fig. 6, is provided with an apertured inner end c^3 which is secured in position by a pin c^4 , provided with a head c^5 which is received in a countersink or recess c^6 in the apertured inner end.

The guard c is preferably provided with a lining of felt or other cushioning material c^7 on the side c^2 , and the outer surface c^8 may be provided with strips or disks of suitable material or substance bearing numbers or other data, or with a writing surface for marking data thereon, corresponding or relative to the disk records within the cell.

Means are provided on the guard c , such as, for example, spring controlled buttons or pins k , for automatically engaging with notches or recesses k^1 formed in the inner surfaces of the end walls of the cells. The buttons engage with the recesses when the guard is in the closed position, as shewn in the lower half of Fig. 2, and thereby lock the disk records within the cell which is rather important when removing or transporting a cell with its records. The disengagement of the buttons from the recesses, which may be effected by a sharp lateral pull on the guard c , enables the latter to be moved to the open position, as shewn in the upper half of Fig. 2. When the guard is moved to the open position, all the disks controlled thereby, move automatically down the inclined bottom b to the position shewn in the upper half of Fig. 2, so that one or all can be readily withdrawn. In this way an automatic discharge of the records can be obtained without the necessity for using expensive lever and other arrangements as at present. When the guard c is in the open position, it is held and supported in a predetermined set position by blocks c^9 secured to the walls of the cell. Safety chains c^{10} may also be employed for this purpose.

To prevent the cabinet tilting over or being readily tilted over when one or both

guards are in the open position and disk records moved into or are in engagement therewith, the front legs j^4 are forwardly pitched, and the lower ends thereof, which 5 terminate in outwardly curved feet, contact with the floor in front of the vertical plane passing through the centres of gravity of all the disk records when in the outermost position resting against the open guard or 10 guards.

Disk records of different sizes may be housed in cells constructed as herein set forth, and can be securely supported by the 15 guards when the latter are in the open position. It will be noted from Fig. 2 of the drawings, that the distance between the guard c and the front edge of the upper wall of the cell, is more than the diameter of the disk records, so as to provide free 20 passage for the disk records to and from the cells in the cabinet. All the disk records are moved collectively into the cell provided therefor, by raising the guard c and moving it to the closed position, and 25 when both guards are in the closed position, the cells may be closed, and kept free from dust, by the flexible cover d , which may vary in form and construction to meet varying circumstances.

30 In the cabinet shewn at Figs. 1 and 2, a roll-top cover d is used as the flexible cover, being formed of a series of wooden or other slats or bars d^1 , connected together by flexible means such as a backing of textile 35 material. The roll-top cover is arranged with each edge thereof in a groove d^3 , one being formed in each side j of the cabinet. Preferably, each groove d^3 comprises a horizontal portion located above the level of 40 the upper wall of the top cell and downwardly extending portions at the front and rear of the cabinet, the horizontal portion communicating with the downward portions by curved portions d^4 which facilitate the 45 passage of the roll-top cover as it is moved lengthwise to and from a position in front of the cells. The roll-top cover is fitted with an end slat or bar d^5 formed with a finger grip recess d^6 for facilitating the 50 movement of the cover, and with a lock d^7 at one or both ends, so arranged, that the bolt or bolts thereof, when inserted or moved to the locking position extends or extend 55 from one or both ends of the end bar d^5 . Each bolt may be spring controlled to the outward position and operated inwardly by a key, or the movement in each direction 60 may be controlled by a key. The locking means provided at one or both ends of the bar d^5 serves or serve for securing the roll-top cover in one or more positions for closing one or more cells, and for this purpose the bolt or bolts thereof is or are engaged 65 with apertures d^8 formed where shewn in the grooves d^3 .

An alternative construction of flexible cover d , is shewn in Fig. 3 and comprises a length of flexible fabric in the form of a blind, mounted on a roller d^9 , preferably a spring controlled roller, supported on the 70 sides j near the top j^2 . The blind may be provided with a bar d^5 fitted with locking means having a bolt or bolts for engaging apertures in the sides j .

A cabinet constructed as hereinbefore described may be fitted with one cell when first acquired, and afterwards, a second cell 75 may be obtained and easily and quickly fitted into position. The cells are constructed as self-contained articles, and are adapted for sale independently of the cabinet, and where the cabinet is constructed to hold a number thereof, the separate cells may be obtained as and when required for fitting 80 into the cabinet. One of such self-contained cells is separately shewn in Fig. 7.

Although only one form of cabinet is shewn in the drawings, it will be obvious 85 that the same may be constructed for holding a series of cells one above the other, and (or) on each side, and for holding cells of varying sizes as to height or width.

It will be understood that considerable 90 variation may be made in the details of construction of the several parts constituting the improved cabinet without departing 95 from the nature of the invention. For instance, it is obvious the guard may be mounted on the sides j of the cabinet instead of the end walls of the cell; or a different 100 means, such as, a hand operated bolt or bolts, may be provided on the guard for securing it in the closed position; or the partitions may not extend to the back of the cells and 105 may be held in spaced relationship by slotted or tongued bars g secured to the upper and lower walls of the cells, and so on.

A cabinet as shewn can be cheaply built, 110 there being no hinged doors to provide; it has a neat appearance; the records can be promptly stored or removed; it is not necessary to pull or force out the records as they run forwards automatically into position for removal; and when it is required to close 115 the cabinet it can be smartly done by turning up the guards, thereby automatically forcing the records into stored position, and pulling down the roll-top or the blind as the case may be.

The roller blind design of cabinet constitutes 120 a very neat and cheap arrangement. The blind may be ornamented or have the name and mark of the maker conspicuously shewn thereon.

Having now fully described my invention, 125 what I claim and desire to secure by Letters Patent is:—

A filing cabinet having a compartment sub-divided into a plurality of sections open and unobstructed at their ends, the sections 130

being designed to contain disk records, a
forwardly and downwardly inclined bottom
for said compartment upon which the
records normally rest, arms pivoted at their
lower ends upon each side of the cabinet,
which arms are adapted to move outwardly,
a rail carried by the free ends of said arms
and normally extending transversely of and
in abutting relation to said sections to retain

the records therein, and means connecting 10
said arms with said cabinet to limit the for-
ward movement thereof, whereby on moving
said rail downwardly all of the records in
each of the said sections will roll down said
bottom in abutting relation to said rail until 15
the latter reaches its lowermost position.

In testimony whereof I affix my signature.
HUGH D. FITZPATRICK.
